UNITED STATES PATENT OFFICE.

JOSEPH B. SARGENT, OF NEW HAVEN, CONNECTICUT.

DESIGN FOR BRACKETS.

Specification forming part of Design No. 7,503, dated June 23, 1874; application filed April 22, 1874.
[Term of Patent 14 years.]

To all whom it may concern:

Be it known that I, JOSEPH B. SARGENT, of New Haven, in the county of New Haven and State of Connecticut, have invented a new Design for Shelf-Bracket; and I do hereby declare the following, when taken in connection with the accompanying drawing and the letters of reference marked thereon, to be a full, clear, and exact description of the same, and which said drawing constitutes part of this specification, and represents a side view.

This invention relates to a design for cast-metal shelf-bracket; and consists in the peculiar configuration of the filling between the frame and brace, as shown in the accompanying illustration, and more fully hereinafter described.

The upright and arm are at substantially

right angles to each other, and the brace extends from near the lower end of the upright to the outer end of the arm, forming a "spandrel," which is filled by a succession of rings, each connected to the next, and the outer rings to the upright, the arm, or the brace where they come in contact, as shown.

This filling of the spandrel constitutes the peculiar feature of this design.

I claim as my invention—

The design for bracket, consisting of a frame filled by a succession of connected rings, as shown in the accompanying illustration, and herein described.

JOSEPH B. SARGENT.
